UNITED STATES PATENT OFFICE.

MARCÉL BARRÉS, OF SANTIAGO, CHILE.

HORSESHOE-MAKING MACHINE.

Application filed November 23, 1922. Serial No. 602,769.

To all whom it may concern:

Be it known that I, MARCÉL BARRÉS, citizen of the Republic of France, residing at Santiago de Chile, have invented new and useful Improvements in Horseshoe-Making Machines, of which the following is a specification.

This invention relates to an improved machine for bending metal bars, the object of the invention being to provide a machine of this character by means of which metal blanks that have been previously rolled and cut to the required dimensions may be uniformly bent into the desired shape without the use of heat, whereby the production of the completed article is accomplished expeditiously and economically, the machine being particularly well adapted for the formation of horseshoes and similar articles.

With the foregoing and other objects in view, which will appear as the description proceeds, the invention consists in the novel features of construction and combination of parts which will be more fully described hereinafter and particularly pointed out in the claims.

In the drawings accompanying and forming part of this specification:

Fig. 1 is a plan view of a machine embodying the features of the present invention;

Fig. 2 is a vertical sectional view taken on the line A—B of Fig. 1; and

Fig. 3 is a vertical sectional view taken on the line C—D of Fig. 1.

The same characters of reference designate the same parts in the different figures of the drawings.

Referring to the drawings, 23" designates a standard or pedestal, preferably of hollow formation, as indicated at 23', said standard merging at its lower end in a flanged base 23 adapted to be secured by means of bolts 25 to a suitable foundation (not shown). At its upper end the pedestal merges into an enlarged head or platform 24, the upper surface of which is cut away at one portion thereof to receive a work table 13 of approximately semicircular form, which is secured to the head 24 by means of bolts 26, the top surface of the table 13 being in the same horizontal plane with the top surface of the extended table portion 15 of the head. The pedestal is provided with

webs 28 and 30 for giving additional support to the table portions 13 and 15.

The table 13 is provided with a guide slot 14 of approximately horseshoe shape, within which operates a roller 2 pivoted on a stud 3 secured in a pair of bifurcated members 1 which are fastened by bolts and nuts 4 to an operating handle 5, the members 1 and 5 thus constituting a hand lever adapted to fulcrum on the walls of the slots 14 in the table. As clearly shown in Fig. 2, the members 1 are spaced sufficiently far apart to straddle the table 13. The member 1 that overlies the table 13 is of enlarged formation, forming a cam-like nose at its inner ends, as shown in Fig. 1.

Secured in the table 13 and extending upwardly therefrom are a pair of studs 12 located in the space encompassed by the slot 14, said studs being threaded at their upper ends to receive nuts 12'. The studs 12 carry a vertically movable presser head 8 and a pressure receiving member 8'. Through the head 8 is threaded a pressure screw 11, the lower end of which rests on the pressure receiving member 8', said screw being provided at its upper end with a cross lever 9 carrying a pair of operating handles 10 by means of which the screw 11 may be rotated to exert pressure on the member 8'. The studs 12 are of such length as to provide space between the underside of the member 8' and the table 13 for the reception of a pattern or model 6 and an overlying member or cover 7 of greater width than said pattern whereby the member 7 overhangs the pattern around its edge so as to form a marginal space between the table 13 and the member 7 around the edge of the pattern 6. The said pattern is provided with a heel or stop portion 27 for engaging the end of the metal bar to be bent, as hereinafter described.

For securing the metal to be operated upon in the machine, a curved detent member or dog 17 is pivoted at 18 on the table 13 in such position that its free end is adapted to be swung under the member 7 and into engagement with the pattern at a point contiguous to the stop portion 27, and for exerting pressure on said detent member a screw 19 is mounted in brackets 20 and 21 secured to the table 13, said screw being thread connected with bracket 20 and pro-

vided at its outer end with a hand lever 22 for rotating the screw.

The operation of the machine is as follows: The nuts 12', together with the members 8, 8' and 7 are removed from the studs 12. A plate or pattern 6, the contour of which corresponds to the shape to which it is desired to bend the metal bar, is then placed in position on the table, the pattern 10 being provided with a pair of perforations for the passage of the studs 12. The members 7, 8' and 8, as well as the nuts 12' are then replaced and the screw 11 rotated by means of the handles 10 so as to exert pressure on the pressure receiving member 8' and thereby securely clamp the pattern in place. A blank 16, which has been previously rolled to the proper thickness and cut to the exact length required, is inserted 15 with one of its extreme ends between the free end of the detent 17 and the edge of the pattern, said blank being pushed in until its inner end abuts against the stop or abutment 27, whereupon the screw 19 is rotated 20 by means of its lever 22 thereby to exert pressure on the detent 17 and cause it to securely clamp the end of the blank 16 against the edge of the pattern 6 and beneath the overhanging edge of the member 7. The 25 operator then takes hold of the lever 5, and by a succession of short reciprocating strokes during which the roller 2 fulcrums against the side walls of the slot 14 in the table 13 the camlike nose 1 of the lever engages the blank 16 at successive points and forces it into intimate contact with the pattern, in a manner which will be readily understood. After the article has been com-

pletely formed, the members 8, 8' and 7 are released from the studs so as to permit the 40 pattern to be lifted and the formed article removed from the machine.

It will be understood, of course, that patterns of various sizes and shapes may be used, and although for purposes of illustration the machine has been described in connection with the formation of a horseshoe, it is by no means limited thereto.

Having thus described my invention, what I claim is:

1. A machine for bending metal blanks, comprising, in combination, a supporting table, means for securing a pattern on said table, means for securing one end of a blank against the pattern, and a lever adapted to engage said blank at successive points and force the same into contact with the pattern, said lever and table having one a slot and the other a roller adapted to engage the walls of the slot thereby to guide said lever and form a fulcrum therefor.

2. A machine for bending metal bars, comprising, in combination, a supporting table, means for securing a pattern on said table, means for securing one end of a blank against the pattern, and a lever adapted to engage said blank at successive points and force the same into contact with the pattern, said table having a slot encompassing said pattern and said lever having a roller projecting into said slot and adapted to engage the walls thereof thereby to guide the lever and form a fulcrum therefor.

In testimony whereof I have signed my name to this specification.

M. BARRÉS.
